US00D952491S

(12) **United States Design Patent** (10) **Patent No.:** **US D952,491 S**
(45) **Date of Patent:** **** May 24, 2022**

(54) **TORQUE SENSOR**

(71) Applicant: **NIDEC COPAL ELECTRONICS CORPORATION**, Tokyo (JP)

(72) Inventors: **Takayuki Endo**, Sano (JP); **Arisa Otake**, Sano (JP)

(73) Assignee: **NIDEC COPAL ELECTRONICS CORPORATION**, Tokyo (JP)

(**) Term: **15 Years**

(21) Appl. No.: **29/736,162**

(22) Filed: **May 28, 2020**

(30) **Foreign Application Priority Data**

Nov. 29, 2019 (JP) 2019-026612

(51) **LOC (13) Cl.** **10-05**

(52) **U.S. Cl.**

USPC **D10/83**

(57) **CLAIM**

The ornamental design for a torque sensor, as shown and described.

DESCRIPTION

FIG. 1 is a perspective view of the torque sensor;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown are included for the purpose of illustrating portions of the torque sensor that form no part of the claim.

1 Claim, 7 Drawing Sheets
